Louis Revost, ATTORNEY

UNITED STATES PATENT OFFICE.

CHARLES R. LAMB, OF NEW YORK, N. Y.

ART OF MURAL DECORATION.

Application filed November 3, 1924. Serial No. 747,682.

My invention relates generally to the decoration of the interior wall surfaces of churches and other buildings and the object of my improvements is to provide an artistic means of decoration which shall at the same time be durable and fire proof. In the method, heretofore employed in order to effect fire proof mural decoration it has been necessary for the artist to apply the decorative medium as mosaic or stucco in situ, directly to the surface to be decorated. My invention, however, enables the decorative scheme to be worked out in the artist's studio and then transported to the place where it is to be applied and at the same time it presents a surface which will not be affected by fire as are oil paintings, whether applied directly to the wall or to canvas. For the purpose of illustrating the preferred embodiment of this invention I have shown in the accompanying drawing a design applied to a canvas or other suitable backing and in this drawing Figure 1 is a plan and Figure 2 a sectional view. In the accompanying drawing I have endeavored to illustrate my invention graphically and have shown in Figure 1, a plan view picture executed in accordance with my invention, by applying portions of different colored cements upon a backing of canvas, or other similar material, indicated at 1, the cement portions uniting to form an integral body, indicated at 2, made up of the several portions of different colored cements, to give the desired decorative results, and solidified into a unitary body. In Figure 2, I have shown a sectional view in which different portions of the cementitious body, 2, of different colors, although integral with each other, are shaded to represent different colors, the cementitious body, 2, being pressed upon, and in this instance partially at least, through the interstices of the backing, 1, and being represented in a somewhat exaggerated manner at 2^a, where they have penetrated the backing, thus locking the cementitious body, 2, and the backing, 1, firmly together.

In carrying my invention into effect I mix dry colors each with a suitable cement, as 50 Portland cement, which is wetted, as with water, to form separate plastic masses.

If desired the plastic masses of cement may be first formed and the dry colors then thoroughly mixed with each. In practice, 55 however, I prefer to form batches of mixtures of the various dry colors employed

with dry cement which was then wetted by the artist, so as to form plastic masses, as required for use. The various colors thus prepared are then applied, so as to form the desired decorative design, to a suitable fabric such as canvas, or burlap, and the plastic material is pressed into and through the fabric, so that the fibres of the fabric are covered by and imbedded in the plastic material. It will be understood that the separate masses of plastic cement compound, each given a different color, corresponds to an artist's palette, and that portions of the different colored masses are applied to the flexible fabric backing so as to produce in reality a mosaic, the marginal portions of the adjacent plastic masses, however, uniting while moist and plastic, so as to leave no visible lines of demarkation, as in true mosaics. The result, therefore, has all the appearance of an oil painting with an extremely virile and characteristic texture, which is very pleasing to the eye, and adapts this decoration particularly to mural purposes, where it is viewed from a considerable distance, the distance slightly softening the apparent texture of the surface without losing its character, as does an oil painting viewed from a considerable distance. At the same time, the structure of the decoration is that of a mosaic in effect, because the colored portions extend from the front clear through to the back, while it differs from a mosaic in that when it is dry, the several differently colored portions have united around their contiguous edges, so that the surface is in fact an absolutely integral thing, although it is supported by the canvas backing, which permits it to be transported without injury or breakage.

If desired such portion of the cement as has passed entirely through the fabric may be smoothed over so as to make a uniform coating over the back of the fabric.

The surface of the cement may also, if desired, be washed with a fire resisting solution, such as silicate of soda, to further increase its fire resisting properties.

The fabric thus prepared is then attached to the wall to be decorated in any suitable manner as by being adhesively secured thereto by suitable cementitious material such as white lead.

The fabric formed as described is impervious to moisture, is not inflammable and will not be injured by fire as will ordinary

oil paintings. It can when dry be rolled and transported from place to place thus enabling the decorative work to be done in the artist's studio and only requiring the labor of skilled workmen to attach it to the wall to be decorated.

The artistic effect of the cement medium laid on to a fabric, such as canvas, in the manner described is also materially different from that produced by painting in oils, having more the effect of a mosaic, as well as the durability and fire resisting qualities of that form of decoration and securing the artistic result in the decoration which has heretofore been produced only by mosaic. It is well known that the use of oil paintings on canvas for mural decorations is attended with a considerable fire risk, and with certain other disadvantages. For example, in case of a fire attacking such oil paintings, they burn readily, and contribute fuel to the fire. Even if not actually burned, but merely exposed to flame or smoke, they are in most cases permanently injured, or utterly ruined, as either high heat, a flash of flame or smoke, is extremely injurious, and in most cases destructive to oil paintings. In the use of my improved mural decorations, they are absolutely fire proof, and if exposed to flame or smoke, or high temperature, they are not permanently injured, and may be readily cleaned. My improved mural decorations may also be washed down with a hose, or otherwise treated with water, without any injury whatever, which makes them very desirable for use in places where sanitary conditions must be maintained; and where at the present time the use of oil paintings for decorative effects is prohibitive.

Having thus described my invention what I claim as new and desire to secure by Letters Patent is:—

1. A method of mural decoration, which consists in forming separate plastic masses of cement mixed with different dry colors, and applying portions of such differently colored masses directly to different portions of a flexible fabric, according to an artistic decorative design, in such manner that the entire surface of the fabric will be covered and the contiguous marginal portions of plastic masses of different colors will unite while in moist condition, to form an integral sheet.

2. A method of mural decoration, which consists in forming separate plastic masses of cement mixed with different dry colors, and applying portions of such differently colored masses directly to different portions

of a flexible fabric, according to an artistic decorative design, in such manner that the entire surface of the fabric will be covered and the contiguous marginal portions of plastic masses of different colors will unite while in moist condition, to form an integral sheet, and forcing the several masses of differently colored cement plastic into and through the meshes of the flexible fabric, to interlock them therewith throughout the entire extent of the design.

3. A method of mural decoration, which consists in forming separate plastic masses of cement mixed with different dry colors, and applying portions of such differently colored masses directly to different portions of a flexible fabric, according to an artistic decorative design in such manner that the entire surface of the fabric will be covered and the contiguous marginal portions of plastic masses of different colors will unite while in moist condition, to form an integral sheet, drying the plastic material, and adhesively securing the fabric to the wall to be decorated.

4. A method of mural decoration, which consists in forming separate plastic masses of cement mixed with different dry colors, and applying portions of such differently colored masses directly to different portions of a flexible fabric, according to an artistic decorative design in such manner that the entire surface of the fabric will be covered and the contiguous marginal portions of plastic masses of different colors will unite while in moist condition, to form an integral sheet, and washing the surface of the cementitious material with a fire resisting solution to further increase its fire resisting properties.

5. A method of mural decoration, which consists in forming separate plastic masses of cement mixed with different dry colors, and applying portions of such differently colored masses directly to different portions of a flexible fabric, according to an artistic decorative design, in such manner that the entire surface of the fabric will be covered and the contiguous marginal portions of plastic masses of different colors will unite while in moist condition, to form an integral sheet, drying the cementitious material, and securing the fabric to the wall to be decorated with non-inflammable cementitious material.

In testimony whereof I affix my signature this 31st day of October, 1924.

CHAS. R. LAMB.
